UNITED STATES PATENT OFFICE.

CLARENCE D. PORTERFIELD, OF NEW YORK, N. Y.

RAIL-ANCHOR.

1,136,612.

Specification of Letters Patent. Patented Apr. 20, 1915.

Application filed June 24, 1914. Serial No. 846,988.

To all whom it may concern:

Be it known that I, CLARENCE D. PORTERFIELD, a citizen of the United States, residing in New York city, in the county of New York and State of New York, have invented certain new and useful Improvements in Rail-Anchors, of which the following is a specification.

My invention pertains to anchors for preventing railroad rails from creeping.

It comprises but two parts, an anchor and a wedge, both blanked from steel plates and stamped and bent into their final forms, and therefore economical and adapted to be turned out in great quantities by automatic machines.

The improvement in my device consists in making it from a sheet metal stamping, and is therefore resilient, and so arranging the structure that any creeping of the rail which it grips, deforms or distorts the device. This distortion causes an increase in the grip of the anchor upon the rail, through the foreshortening of the sides of the triangularly disposed base grips, and which foreshortening, together with the above noted resiliency of the device, forms the important part of my invention.

Figures 1, 2 and 3 are perspectives. Fig. 1 shows the rail base and web in section and the mode of putting on the anchor, Fig. 2 shows it in place. Fig. 3 shows one side of the rail and the anchor head. Fig. 4 is a plan view.

The rail is of common section, with base flanges 2, 2, and is spiked to the tie, 1, as usual. The anchor 3 is blanked from steel plate and bent into the shape of a 7. It has a head, 30, broadest at its free edge for a large abutting face 35, and a narrow tang, 31, terminating in a wider butt 32. Flange notches 33, to fit closely on the margins of the base are located in the free end of the head and in the inner side of the butt 32, and a wedge notch, 34, to fit the base margin and wedge, is blanked at the junction of the head and tang. The distance from the root of the wedge-notch 34 to the fluke, 37, of the opposite flange-notch, slightly exceeds the width of the rail base, so that the anchor can be put on the rail.

The notched anchor plate is bent into shape, the end of the head bent inward to form a tie face 35; and the head flukes 36 are bent outward and the butt flukes 37 bent inward to facilitate putting the anchor on the rail-base. The wedge 4 is tapered, offset to fit on and ride the rail-flange and slotted to form a narrow fork 40.

To apply the anchor, the tang 31 is passed nearly at right angles under the rail base with the notches upward and the wedge-notch 34 riding the rail-base. The tang 31 is then raised to the base and the butt 32 swung toward the abutting face 35 to cause the butt-flukes 37 to ride the base and the free head fluke 36 to clear it; whereupon the bearing end 35 of the head is raised, and the wedge 4 is inserted from within the head, into the wedge notch 34 and riding the rail base, which draws the anchor into sliding engagement with the rail base. The anchor is then driven home, with its face 35 against the tie 1, the wedge 4 is forced home with a crow-bar which is wedged between the end of said wedge and the inner face of the butt 35, and its fork 40 of the wedge is bent down, to lock the anchor. This mode of application puts the anchor under triangular stress, as indicated by the dotted triangles and the dotted and full lines of the head, in Fig. 4.

It is obvious that the head 30 resists creeping stresses elastically and therefore is not likely to gouge the tie as rigid anchors do, and is even more reliable in its action; and also that use tightens the grip of the anchor to the base because of the obliquity of the tang 31 to the rail and the projection of the head 30 therefrom.

It is obvious from the foregoing that owing to the use of the wedge and the resiliency of the anchor, which resiliency is preferably maintained by tempering the steel, this device may be used to prevent creeping of the rail in either direction, or, in other words, is reversible. For instance, by referring to Fig. 4 it will be seen that the end 35 bears against the tie 1, but it is also obvious that the device can be turned around in the opposite direction and the wedge end placed against the tie, and that the same

forces acting under distortion of the anchor would still tend to lock the anchor upon the rail.

Having thus described my invention, I claim:—

1. A non-creeping rail anchor adapted to engage a railroad rail and tie comprising a tang having oppositely located resilient rail-base gripping members arranged thereon, one of said gripping members abutting against the tie, and a wedge for increasing the tension therebetween.
2. A non-creeping rail anchor adapted to engage a railroad rail and tie comprising resilient oppositely arranged rail-base engaging members integrally connected, one of said base-engaging members abutting against the tie, and tension increasing means between said resilient members.
3. A non-creeping rail anchor comprising resilient oppositely arranged rail-base engaging members integrally connected, tension increasing means between said resilient members, and locking means carried by said tension-increasing means to maintain the same in operative position.
4. A non-creeping anchor adapted to engage a railroad rail and tie and comprising a tang adapted to extend obliquely across the rail-base and integral therewith, and oblique thereto a head adapted to abut against a tie, flukes extending from said tang and head and forming flange-notches and a wedge-notch, and a wedge driven into said wedge notch, straining the anchor upon the rail base.
5. A non-creeping anchor adapted to engage a railroad rail and tie and comprising a tang adapted to extend obliquely across the rail-base and integral therewith, and oblique thereto a head adapted to abut against a tie, flukes extending from said tang and head and forming flange-notches and a wedge-notch, a forked wedge driven into said wedge-notch with one fork riding the rail-flange and the other bent down on the anchor.
6. A non-creeping anchor adapted to engage a rail and tie and comprising an anchor cut from a metal plate, formed with a narrow tang and a broader head, flange notches and a wedge notch, said head bent obliquely to said tang and its free end bent inwardly to form an abutting face; and a wedge cut from a sheet of metal; said tang adapted to extend obliquely across the rail base, said notches to engage the rail flange and said wedge driven into said wedge socket.
7. A new article of manufacture, a non-creeping anchor for railroad rails, cut from a metal plate, formed with a narrow tang and a broader head, flange notches and a wedge-notch, said head bent oblique to said tang like the digit 7.
8. A new article of manufacture, a non-creeping anchor for railroad rails, cut from a metal plate, formed with a narrow tang and a broader head, flange notches and a wedge-notch, said head bent oblique to said tang like the digit 7, and its free end bent inwardly to form an abutting face.
9. A new article of manufacture, a non-creeping anchor for railroad rails, blanked from a metal plate, formed with a narrow tang, a broader head and flukes forming flange notches and a wedge notch, said head bent oblique to said tang and its free end bent inward to form an abutting face and said flukes bent relatively to said tang and head.
10. A new article of manufacture, a non-creeping anchor for railroad rails, blanked from a metal plate formed with a tang, a head and flukes forming flange notches and a wedge notch, and bent into shape like a 7.
11. A new article of manufacture, a non-creeping anchor for railroad rails, blanked from metal plate formed with a tang, a head and flukes forming flange notches and a wedge notch bent into shape like a 7 with the tang oblique to the head of the flukes bent.
12. A new article of manufacture, a non-creeping anchor for railroad rails blanked from elastic steel plate, formed with a tang, a head and flukes forming flange and wedge notches, bent into shape like a 7.
13. A new article of manufacture, comprising a non-creeping anchor for railroad rails blanked from metal plate formed with a tang, a head and flukes forming flange notches and a wedge notch, bent in the shape of a 7, with the tang oblique to the head and the flukes bent, and a wedge driven into said wedge notch.
14. A new article of manufacture, comprising a non-creeping anchor for railroad rails blanked from metal plate formed with a tang, a head and flukes forming flange notches and a wedge notch, bent in the shape of a 7, with the tang oblique to the head and the flukes bent, a wedge driven into said wedge notch, and means on said wedge for maintaining the same in operative position.
15. The combination with a rail, of a tempered steel rail anchor comprising a tang having oppositely located resilient rail-flange gripping members arranged thereon, one of said gripping members abutting against the tie and means for increasing the tension of said gripping members upon said flange.
16. A non-creeping rail anchor adapted to engage a railroad rail and tie comprising a tang having a rail engaging fluke at one end; a resilient head at its opposite end, said head having a rail engaging member at each of its ends, one of which abuts against the tie; and a wedge cooperating with one of the

ends of said head to increase the tension between said flukes and said head.

17. A non-creeping rail anchor adapted to engage a railroad rail and tie comprising a tang having a rail engaging fluke at one end, a head at its opposite end; said head having a rail engaging member at one of its ends, a wedge receiving portion at its other end, and a resilient intermediate portion be-

tween and integral with the rail engaging end and the wedge receiving portion; and a wedge coöperating with the wedge receiving portion to increase the tension between said flukes and said head.
